UNITED STATES PATENT OFFICE.

EDMUND B. MILLER, OF DANDRIDGE, TENNESSEE.

FENCE AND POST LIFTER.

SPECIFICATION forming part of Letters Patent No. 311,138, dated January 20, 1885.

Application filed October 4, 1884. (No model.)

To all whom it may concern:

Be it known that I, EDMUND B. MILLER, a citizen of the United States, residing at Dandridge, in the county of Jefferson and State of Tennessee, have invented certain new and useful Improvements in Fence and Post Lifters; and I do hereby declare that the following is a full, clear, and exact description of the invention, reference being had to the accompanying drawings, forming part of this specification, in which—

Figure 1 is a side elevation of my improved fence and post lifter with one of the wheels removed. Fig. 2 is a plan view of the same machine.

My invention relates to means for raising posts and corners of fences which have sunk too low into the ground; and it consists in the detailed construction and combination of parts, hereinafter fully described, and shown in the accompanying drawings.

Similar letters indicate corresponding parts in both figures.

A is a crow-bar, the point of which is inserted under the corner of the fence to be lifted.

B is a rack fastened on the upper side of crow-bar A, the teeth of which gear into the teeth on a segment, C, which is firmly secured to the lever D for working the machine. The end of lever D projects beyond the segment C, and is formed with a radius or curve on the top corner, over which a flat link-chain, E, is stretched. One end of this chain is securely attached to the lever D by the fastener e, and the other is attached to the crow-bar by the eyebolt e'. Guide-plates e² are attached to the sides of the lever to keep the chain from slipping off.

F is the axle, provided with wheels f for moving the machine about. The wheels f run loose on the ends of the axle F, which is secured to a casting, G, extending between the wheels, and provided with projecting portions g, which form a bed for the crow-bar A to slide on.

H are brackets, one of which is bolted on either side of the crow-bar to the casting G, and provided with a pin, h, in the upper part of them, which forms a pivot for the lever D and toothed segment to work on.

I is a handle securely bolted to the casting

G and bent upward, with a loop, i, at the end of it, which may be sprung over a pin, d, projecting from the side of lever D.

J is a scotch-lever, formed with a double end, j, pivoted to the axle F of the machine. The end of lever J away from the axle is provided with a downwardly-projecting point, j', for digging into the ground. The space between the forks j of the lever is filled in with wire-netting, and may be used for removing large stones which are too heavy to carry and may be in the way of the machine. The stones can be dragged up onto the netting when the lever J is on the ground, and the machine wheeled along for some distance and the stones pushed off out of the way.

K is a chain, one end of which is made fast to the lever J and the other to the end i of the handle I. A hook, d', is attached to the side of lever D.

When it is desired to couple the lever J to the lever D, one of the links in the chain K is passed over this hook.

The operation of the machine is as follows: When it is desired to raise the corner of a fence, the lever D is thrown upward into a nearly vertical position, as shown by the dotted lines in Fig. 1, with the crow-bar pointing downward. The machine is wheeled close to the fence by pushing it along with the handle I. The chain K is unhooked from the lever D and the scotch-lever J pressed downward, so that the point j' enters the ground and prevents the machine from running backward. The operator, who keeps his feet on lever J to prevent it from slipping up, grasps the handle I with his left hand, and with his right pulls the lever D toward him. The movement of the toothed segment causes the crow-bar A to advance and dig into the ground underneath the corner of the fence, and a continuation of the movement of lever D to the position shown by full lines in the drawings raises the post or fence corner, which may then be blocked up to the required height.

Having thus described my invention, what I claim as new, and desire to secure by Letters Patent, is—

1. In a fence and post lifter, the combination of the crow-bar A, having a toothed rack, B, fastened to the upper side of it, with the lever

D, having a toothed segment, C, and with one end of it projecting beyond said toothed segment, and the chain E, attached to the crow-bar A and extending over the projecting end 5 of the lever D, to which it is also attached, substantially as described and shown.

2. In a fence and post lifter, the combination of the crow-bar A, having a toothed rack, B, the lever D, having a toothed segment, C, and 10 with one end projecting beyond said segment, chain E, attached to crow-bar A and extending over the projecting end of lever D, fastener e, for attaching said chain to lever D, and guide-plates e', attached to the sides of the lever, substantially as shown and specified. 15

3. In a fence and post lifter, the combination of crow-bar A, having toothed rack B, lever D, having toothed segment C, chain E, attaching said crow-bar to said lever, brackets H, in 20 which lever D is pivoted, casting G, provided with the projecting portions g, and axle F, provided with wheels f for moving the machine about, substantially as described and shown.

4. The combination of crow-bar A, having

toothed rack B, lever D, having toothed segment C, chain E, attaching said crow-bar to said lever, brackets H, in which said lever is pivoted, casting G, provided with projecting portions g, axle F, provided with wheels f, and handle I, secured to casting G and provided 30 with the looped end i for engaging with pin d in lever D, substantially as shown, described, and set forth.

5. The combination of the lever J, pivoted on axle F and provided with an end, j', for digging into the ground, chain K, handle I, having the looped end i, lever D, having toothed segment C, pin d, and hook d', chain E, crow-bar A, having toothed rack B, brackets H, in which lever D is pivoted, casting G, provided 40 with projecting portions g, and axle F, mounted on wheels, substantially as shown and described, and for the purpose set forth.

EDMUND B. MILLER.
